UNITED STATES PATENT OFFICE.

HERBERT L. DICKEY, OF DETROIT, MICHIGAN.

LIFTING JACK.

Application filed March 25, 1924. Serial No. 701,861.

To all whom it may concern:

Be it known that I, HERBERT L. DICKEY, a citizen of the United States, residing at Detroit, in the county of Wayne, and State 5 of Michigan, have invented certain new and useful Improvements in Lifting Jacks, of which the following is a specification.

This invention relates to a lifting jack. It is especially designed to fulfill the requirements of the trade for a jack that may be low in price but yet sturdy enough to do the required work. It is common practice to furnish all cars at the factory with a set of tools including a jack. Since these jacks 10 must necessarily cost very little, it is my purpose to construct one in which the number of parts has been decreased and the cost of the jack in proportion. I form the several parts of the jack from stampings or malleable castings and provide an easy assembly 15 of the several parts so as to decrease the labor cost.

Another object of the invention is to provide yieldable means forcing the actuating 20 dogs into engagement with the rack bar and an additional spring member for forcing one of the actuating dogs out of engagement with the rack bar, the parts being so arranged that the second mentioned means 25 may be placed in an inoperative position when the rack bar is raised and when the rack bar is lowered this spring means functions so as to throw the lock dog out of engagement but adapted to be momentarily 30 released to allow the locking dog to again engage the rack bar.

Fig. 1 is an elevational view of my improved form of lifting jack.

Fig. 2 is a bottom plan view of the base 35 support.

Fig. 3 is a detail showing the means for locking the reverse lever taken substantially on the line 3—3 of Fig. 1.

Fig. 4 is a detail taken on the line 4—4 40 of Fig. 2, showing how the housing and base support are secured together.

Fig. 5 is a detail showing the working parts of the jack in elevation when using the jack to raise the rack bar.

Fig. 6 is a similar view showing a different position of the actuating parts.

Fig. 7 is a similar view showing the arrangements of parts when the rack bar is being lowered.

Fig. 8 is a view similar to Fig. 7, show-

ing another position of the jack operating parts.

Fig. 9 is a transverse section on the line 9—9 of Fig. 5.

Fig. 10 is a transverse section on the line 10—10 of Fig. 1.

Figs. 11 and 12 are transverse sections similar to Fig. 10 showing modified forms of the rack bar that may be used.

Fig. 13 is a sectional detail taken on the line 13—13 of Fig. 7, showing the offset cam for throwing out the lifting dog.

Fig. 14 is a detail in perspective of the reverse lever.

Fig. 15 is a section on the line 15—15 of 70 Fig. 14.

Fig. 16 is a detail in perspective of the spring tending to force the dogs into engagement with the lock bar.

Fig. 17 is a detail in perspective of the 75 safety-pin type of spring for throwing out the locking dog.

The jack housing *a* is formed of sheet metal suitably blanked out and then formed and assembled together as clearly shown in 80 Fig. 1. This housing is secured to a base *b* of sheet metal, which is suitably ribbed to reinforce the same and enable the housing and base to withstand the severe loads that are carried by the jack. A rack bar *c* is 85 guided vertically within the housing and is provided with the ratchet teeth *d*. As shown in Figs. 10 to 12 inclusive, these teeth are formed by cutting or casting grooves in the face of the rack bar which are concave 90 transversely thereto. In Figs. 11 and 12, I show a modified form of rack bar in which the rack bar is an I-beam section (Fig. 12) and Fig. 11 is an I-beam section formed by securing two channels back to back. In 95 using an I-beam section such as shown in these modified forms, it would be impossible to cut the groove straight across as the cut would break through the flanges of the I-beam and reduce the strength of the same, 100 and the groove concave transversely of the rack bar does not weaken the rack bar. By using this form of rack bar I find that the cost is materially reduced as is also the weight without lessening the strength of the 105 jack.

A stud *e* pivotally supports the operating lever *f* in the housing (see Figs. 5 to 8 inclusive) and the forward end of the lever pivotally supports the lifting dog *h* on the 110

pin or stud *g* carried thereby. The locking dog *i* is pivotally supported on the stud *e* which is the fulcrum of the lever. Obviously, the locking dog has merely a rocking motion while the lifting dog has a reciprocating motion as well as a rocking motion. A spring *j* is coiled about the stud *e* and the stud *g* which pivotally support the locking dog and the lifting dog respectively, 10 the free ends of said spring bearing against the backs of the dogs for forcing the said dogs into engagement with the teeth *d* of the rack bar.

In order to raise the rack bar *c* referring 15 more particularly to Figs. 5 and 6, the operating lever *f* is rocked thus imparting a reciprocating motion to the lifting dog. As the lever is rocked from a position shown in Fig. 5 to that shown in Fig. 6, the lifting 20 dog *h* is pulled downwardly until it reaches a position so that the spring *j* may force the dog into the next lower notch of the rack bar. During this movement the locking dog *k* is in engagement with the rack bar and 25 thus prevents the same from falling while the lifting dog is out of engagement therewith. As the lever *f* is now rocking downwardly it will carry the lifting dog upwardly and thus raise the rack bar the distance of 30 one tooth. While the rack bar is so raised, the locking dog merely rides out of the notch and falls into the next lower notch, whereupon the operation is repeated.

The lowering of the rack bar presents a 35 more complicated problem and in order to obtain the proper actuation of the lifting dog and the locking dog it requires a different actuation of the parts. Pivotally supported on the housing on the pin *w* is a 40 manually operated reverse lever *k* which is provided with an offset cam *m*, which when in the position shown in Figs 5 and 6 when the rack bar is being raised, is in a non-interfering position with the lifting dog. 45 But in Figs. 7 and 8, the reverse lever is lowered or has been rotated in a clockwise direction so as to bring the cam *m* carried thereby into an interfering position with the lifting dog *h*. In Fig. 13, it will be seen 50 how this cam *m* is offset with respect to the plane of the reverse lever so as to lie in the plane of the lifting dog. The edge of the lifting dog is cut away as at *n* for a purpose later to be described.

55 A safety-pin type of spring designated *o* is coiled about the stud *e* one end of which bears down upon the stud *g* which supports the lifting dog, and the other end bearing against the inside edge of the locking dog. 60 The reverse lever is provided with a struck out tongue *p* (Figs. 14 and 15) which is adapted to engage the end of the spring *o* and to hold the same from engagement with the locking dog while the reverse lever is in 65 a position as shown in Figs. 5 and 6. How-

ever, when the reverse lever is lowered the struck out tongue *p* releases the spring *o* and allows the same to bear against the locking dog. While the operating lever *f* is in the position as shown in Fig. 7, the lifting 70 dog is in a raised position which thus tends to wind up the spring *o* so that it will exert a force on the locking dog sufficient to throw the same out of engagement with the rack bar. This spring is so constructed that 75 when it is wound up as shown in Fig. 7, it will overcome the tendency of the spring *j* tending to force the locking bar into engagement with the rack bar, and thereby 80 hold the locking bar out of engagement with the rack bar. As the operating lever is rocked to lower the lifting dog it will unwind the spring *o* and thus decrease the force of the spring bearing against the locking bar to hold the same out of 85 engagement with the rack bar. As the force of the spring *o* is decreased the spring *j* will overcome the spring *o* and force the locking 90 dog into engagement with the rack bar. As the lifting dog is lowered the cam *m* strikes the lifting dog and throws the same out of engagement with the locking bar (see Fig. 8). The timing of the movement of the locking dog and the lifting dog is such that as the lifting dog is lowered the rack will move 95 downwardly therewith and as the locking dog is released from the pressure of spring *o* it will engage the next higher tooth of the rack bar previous to the time when the lifting dog is forced completely out of engagement with the rack bar. As the operating 100 lever is again rocked so as to raise the lifting dog, the cam *m* holds the dog out of engagement with the rack bar until it has raised a sufficient distance and then the spring *j* forces the same into engagement with the rack bar the said lifting dog engaging the next higher notch of the rack bar, whereupon when the operating lever reaches its full stroke the locking dog is forced out of engagement with the rack bar because of the fact that the spring *o* has been wound up and possesses 105 sufficient force to overcome the force of the spring *j*. This cycle of operation will be 110 repeated and the jack is lowered notch by 115 notch until the rack bar has been lowered the required distance.

The housing blank is cut in such a manner that the same may be folded in at the front so as to close the housing at the front with the exception of where the operating lever projects through the housing. The housing is formed with a slot *q* through which the reverse lever *k* is adapted to project. The upper end of the slot is enlarged as at *r* forming the shoulder *s* on which the reverse lever *k* rests when it is pushed up. A coil spring *t* bears against the reverse lever and tends to force the same downwardly but the shoulder *s* is inclined at such an 120 125 130

angle that this downward force tends to push the reverse lever to the left (see Fig. 3) and prevent the same from falling into slot *q*. To use the jack so as to lower the 5 rack bar, it is merely necessary to push the lever *k* from off the shoulder *s* whereupon the spring *t* will force the same down the slot into the position shown in Figs. 7 and 8 whereby the jack may be used to lower 10 the rack bar.

Referring to Fig. 9, it will be noticed that the handle or operating lever *f* is split at the end and flattened as at *u*. The studs *e* and *g* which pivotally support the locking 15 dog *i* and the lifting dog *h* are carried by the flattened end of the lever *f*. The outer end of the lever is tubular in cross section and adapted to receive an operating bar or lever *v* so that one may obtain the necessary 20 leverage to operate the jack. About the pin *w*, which pivotally supports the reverse lever *k*, is a spacing sleeve *x* which is of such a diameter that it will just touch the rack bar and thus guides the rack bar as the same is 25 reciprocated vertically.

What I claim is:

1. In a lifting jack, the combination of a 30 housing, a rack bar guided vertically therein, a lever pivoted in the housing, a lifting dog pivotally supported by the lever for engaging the teeth of the rack, a locking dog pivotally supported for engaging the teeth of the rack, and a differential stressing spring means engaging the locking dog and controlled by the lifting of the lifting dog to cause the spring stress tending to release the 35 locking dog from said rack bar to overcome the spring stress tending to engage the locking dog with said rack bar and controlled by the descent of the lifting dog to cause the spring stress tending to engage the locking dog with said rack bar to overcome the force of the spring stress tending to release the locking dog from said rack bar.

40 2. In a lifting jack, the combination of a housing, a rack guided vertically therein, a pivoted lever supported by the housing, a locking dog, a lifting dog carried by the pivoted lever, the two dogs arranged to engage the teeth of the rack, a spring engaging both dogs for yieldably forcing the same into engagement with the rack, and a spring for engaging the locking dog alone and exerting a counterforce on said locking dog, 45 whereby as the lifting dog is raised by the lever the locking dog is forced out of engagement with the teeth of the rack, and whereby the lowering of the lifting dog reduces the force of the spring tending to release the locking dog to allow the spring 50 for forcing the same into engagement to overcome such counterforce.

60 3. In a lifting jack, the combination of a housing, a rack guided vertically therein, a pivoted lever supported by the housing, a

locking dog, a lifting dog carried by the pivoted lever, the two dogs arranged to engage the teeth of the rack, yielding means operating on the dogs tending to force the same into engagement with the rack, and a 70 safety-pin type of spring, one end engaging the locking dog and the other end engaging the lifting dog whereby the raising of the said lifting dog tends to wind up the spring so that the same will exert a force on the 75 locking dog to disengage the same from the rack and the lowering of said lifting dog unwinds the spring to allow the yielding means to force the locking dog into engagement with the rack.

4. In a lifting jack, the combination of a 80 housing, a rack guided vertically therein, a pivoted lever supported by the housing, a locking dog, a lifting dog carried by the pivoted lever, the two dogs arranged to engage the teeth of the rack, yielding means operated on the dogs for forcing the same into engagement with the rack, and a safety-pin type of spring having one end engaging the locking dog and the other end engaging 85 the stud which pivotally supports the lifting dog, whereby the raising of said lifting dog winds up the spring to force the locking dog out of engagement with the rack while the lowering of the lifting dog disengages the lifting dog from the teeth of the rack bar and unwinds the spring so that the yieldable means may force the locking dog into engagement with the rack bar before the said 90 lifting dog is disengaged from the teeth of said rack bar.

5. In a lifting jack, the combination of a 95 housing, a rack guided vertically therein, an operating lever pivotally supported by the housing, a lifting dog pivotally supported by the pivoted lever, a locking dog supported at the fulcrum point of said lever, the two dogs arranged to engage the teeth of the rack, yieldable means for forcing the dogs into engagement with the rack, and a safety-pin type of spring anchored to the fulcrum of the operating lever and locking dog, and having one end engaging the lifting dog and the other end engaging the locking dog, whereby the raising of the lifting dog winds up the spring to throw the locking dog out of engagement with the rack and the lowering of the lifting dog unwinds the spring to allow the yieldable means to force the locking dog into engagement with the rack.

6. In a lifting jack, the combination of a 110 housing, a rack guided vertically therein, a pivoted lever supported by the housing, a locking dog, a lifting dog carried by the pivoted lever, the two dogs arranged to engage the teeth of the rack, yielding means operating on the dogs to force the same into engagement with the rack, a reverse lever supported by the housing and provided with 115

a cam which may be thrown into an interfering or non-interfering position with the lifting dog, and a spring anchored to the housing and having one end engaging the 5 lifting dog and the other end the locking dog whereby the lowering of the lever winds up the spring and exerts a force on the locking dog to disengage the same from the rack and the lowering of the lifting dog 10 causes the same to strike the cam carried by the reverse lever to throw the lifting dog out of engagement with the rack and unwinds the spring to allow the yielding means to force the locking dog into engagement with the rack.
15 7. In a lifting jack, the combination of a housing, a rack guided vertically therein, a pivoted lever supported by the housing, a locking dog, a lifting dog carried by the 20 pivoted lever, the two dogs arranged to engage the teeth of the rack, a reverse lever provided with a cam offset in the plane of the lifting dog and adapted to be moved into an interfering position with said lifting 25 dog, and yielding means operating on the dogs whereby when the lifting dog is forced downwardly by the lever the yielding means serve to throw the locking dog into engage-

ment with the teeth and the cam carried by the reverse lever strikes the lifting dog to 30 throw the same out of engagement with the rack.

8. In a lifting jack, the combination of a rack bar having ratchet teeth with intervening grooves concave transversely of the rack 35 bar, dogs engaging said ratchet teeth, and means for actuating said dogs to raise or lower said rack bar.

9. In a lifting jack, the combination of a 40 rack bar formed of an I-beam section and having ratchet teeth with intervening grooves concave transversely of the rack bar, dogs engaging said ratchet teeth and means for actuating said dogs to raise or lower the rack bar. 45

10. In a lifting jack, the combination of a rack bar, formed of a pair of channel members secured together back to back to form an I-section, said rack bar having ratchet teeth with intervening grooves concave transversely of the rack bar to form 50 ratchet teeth, dogs engaging said ratchet teeth, and means for actuating said dogs to raise or lower said rack bar.

In testimony whereof I affix my signature.
HERBERT L. DICKEY.
